UNITED STATES PATENT OFFICE.

JOHN G. PAYNE, OF LEAVENWORTH, KANSAS.

HANGER.

1,369,706.

Specification of Letters Patent. Patented Feb. 22, 1921.

Application filed October 27, 1919, Serial No. 333,525. Renewed July 12, 1920. Serial No. 395,764.

To all whom it may concern:

Be it known that I, JOHN G. PAYNE, a citizen of the United States, residing at Leavenworth, in the county of Leavenworth 5 and State of Kansas, have invented new and useful Improvements in Hangers, of which the following is a specification.

This invention relates to a hanger for kitchen utensils, meats, clothing and the like 10 and the principal object of the invention is to provide a hanger which may be suspended from a wall or other support and provided with hooks for receiving the articles to be supported.

15 Another object of the invention is to provide the hanger with a plurality of hooks so supported that the articles may be placed thereon or removed therefrom very easily as said hooks have limited swinging movement.

20 The invention also consists in certain other features of construction and in the combination and arrangement of the several parts, to be hereinafter fully described, illustrated 25 in the accompanying drawings and specifically pointed out in the appended claims.

In describing my invention, reference will be had to the accompanying drawings wherein like characters, denote like or corresponding parts throughout the several views, and 30 in which:—

Figure 1 is a front view of the hanger.

Fig. 2 is a plan view.

Figs. 3 and 4 are detail views.

35 As shown in these views the hanger consists of a base board 1 which at its upper edge is provided with a suspension loop 2. The hook carrying member 3 is formed from one piece of wire having its middle portion 40 brought together and twisted to form the arm 4. From this arm the end portions of the wire are bent at right angles and curved inwardly as shown in Fig. 2. Loops are formed at the end of the arm and at the extremities of the bent wires to receive the supporting nails 5 for holding the wire to the supporting base. The bent ends of the wire are twisted into a plurality of loops 6 which are spaced apart and are adapted to 45 receive the hooks 7. The stems of these hooks are formed with eyelets 8 for engaging the loops 6 and the extreme end of the

stem projects below the eyelet to form a stock 9 to limit the swinging movement of the hook.

55 It will be seen that the arm 4 provides a brace for the middle of the hook carrying member and the hook carrying ends are spaced from the base so as to facilitate the placing of the articles on the hooks as the 60 articles will be held a distance away from the base. By limiting the swinging movement of the hooks the articles may easily be removed from said hooks as the hooks will not be carried upwardly as the articles 65 are raised out of engagement with the hooks.

These hooks are provided with blunt points, ordinary points for clothing and sharp points for use in hanging meats.

70 It will be understood that in some cases the base may be omitted and the member 3 which carries the hooks connected directly to the wall of the room. By the use of the base, however, the danger of defacing the walls by articles suspended from the hooks 75 is obviated. For articles of clothing and the like the base would not be necessary.

76 It is thought from the foregoing description that the advantages and novel features of my invention will be readily apparent.

I desire it to be understood that I may make changes in the construction and in the combination and arrangement of the several parts, provided that such changes fall within the scope of the appended claims.

85 What I claim is:—

1. A device of the class described comprising a base, a bowed member carried thereby, a central supporting arm for the member and hooks carried by the bowed 90 member.

2. A device of the class described comprising a base, a hook carrying member secured thereto and formed from a single piece of wire having a central twisting member forming a supporting arm with the end parts of the wire bent at right angles and curved inwardly from said arm and being twisted to form spaced loops, hooks engaging said loops and means for connecting the 100 extremities of the wire and the arm to the base.

In testimony whereof I affix my signature.
JOHN G. PAYNE.
